(57) **CLAIM**

The ornamental design for a support chair for poured concrete reinforcement members, as shown and described.

DESCRIPTION

FIG. 1 is a perspective view, taken from the top, front, and side, of a support chair for poured concrete reinforcement members, in accordance with a first embodiment of our new design.

FIG. 2 is a top plan view of the support chair for poured concrete reinforcement members shown in FIG. 1.

FIG. 3 is a bottom plan view of the support chair for poured concrete reinforcement members shown in FIG. 1.

FIG. 4 is a front elevation view of the support chair for poured concrete reinforcement members shown in FIG. 1, the rear elevation view being identical thereto

FIG. 5 is a left side elevation view of the support chair for poured concrete reinforcement members shown in FIG. 1, the right side elevation view being identical thereto.

FIG. 6 is a perspective view, taken from the top, front, and side, of a support chair for poured concrete reinforcement members, in accordance with a second embodiment of our new design.

FIG. 7 is a top plan view of the support chair for poured concrete reinforcement members shown in FIG. 6.

FIG. 8 is a bottom plan view of the support chair for poured concrete reinforcement members shown in FIG. 6.

FIG. 9 is a front elevation view of the support chair for poured concrete reinforcement members shown in FIG. 6, the rear elevation view being identical thereto; and,

FIG. 10 is a left side elevation view of the support chair for poured concrete reinforcement members shown in FIG. 6, the right side elevation view being identical thereto.
